UNITED STATES PATENT OFFICE.

CHARLES F. EDSON, OF LOS ANGELES, CALIFORNIA, ASSIGNOR TO LOUIS A. ROY, OF CHICAGO, ILLINOIS.

INTERMITTING APPARATUS FOR COOLING CARS, &c.

No. 865,172.

Specification of Letters Patent.

Patented Sept. 3, 1907.

Application filed June 7, 1906. Serial No. 320,661.

To all whom it may concern:

Be it known that I, CHARLES F. EDSON, a citizen of the United States, residing at Los Angeles, county of Los Angeles, State of California, have invented and 5 discovered a new and useful Improvement in Intermittent Apparatus for Cooling Cars, Warehouses, and the Like; and I do hereby declare the following to be a full, clear, and exact description of the invention, such as will enable others skilled in the art to which it 10 appertains to make and use the same.

This invention relates to improvements in intermittent apparatus for cooling cars, warehouses and the like; and the objects of my improvement are, first, to construct means for reducing the temperature of the 15 atmosphere in warehouses and compartments where perishable articles are kept, and other articles stored that may be damaged by continued high temperatures; and second, to provide an apparatus for cooling cars in which fruits and other articles of food are shipped 20 long distances in hot climates and at seasons of the year when the weather is warm.

The invention consists essentially in the construction, combination and arrangement of the several parts, as will be hereinafter fully described in the specification shown upon the drawings and specifically pointed 25 out in the claims made a part hereof. I attain these objects by the construction, combination and arrangement of the several parts illustrated in the accompanying drawings, in which—

30 Figure 1. is a view partly in elevation and partly in section of a car, parts thereof broken away, showing boxes stored in the car, illustrated in full lines and in dotted lines, and portions of the apparatus at the station of the warehouse for cooling the car after being 35 loaded shown in dotted lines; Fig. 2. is an end view in elevation of the car and a portion of the platform of the warehouse; parts of the apparatus for reducing the temperature of the car shown in full and dotted lines; Fig. 3. is a perspective view, on an enlarged scale of 40 a portion of one of the pipes of my improved apparatus and devices secured thereon for conveniently ascertaining and regulating the temperature of the air within the pipe; Fig. 4 is a perspective view on an enlarged scale of a section of one of the pipes of my apparatus 45 having a thermometer removably fastened within the pipe for conveniently ascertaining and regulating the temperature of the air within the pipe; Fig. 5 is a top plan view of a car shown in full line and a portion of the apparatus illustrated in full and dotted line and 50 parts thereof broken away; Fig. 6 is a view in elevation of the cold coil box or generator for cold air, portions of the pipe connected therewith and levers for operating the valves in the pipes.

Similar reference numerals, letters and characters refer to like parts throughout the several views of the drawings.

The reference numeral 1, denotes the car; 2, 2', indicate boxes of fruit or other perishable articles stored in the central compartment 1', of the car, ready to be shipped; and 3, indicates cleats preferably of wood, 60 placed between the boxes to give a free circulation of air therebetween.

When the car 1, shown upon Figs. 1 and 2 of the drawings, is loaded with boxes 2, and 2', of fruit or other perishable articles it is desirable that the warm or hot 65 air in the car surrounding the boxes be exhausted therefrom and the car before being started on its journey to market, be filled with cold air and with this end in view, the car doors are tightly closed and the valves 20, and 21, shown upon Figs. 5 & 6 of the drawings, are shut down and the exhaust or suction operation of the fan 22, put in operation in order to remove the hot air from the central, storage compartment 1', and it is carried out of the car through the opening 10, in the partition 10', into the tank or compartment 5, 70 thence through the pipe 11, into pipe 12, into pipe 13, thence into pipe 14, into the outer air. The construction of the fan 22, shown upon Figs. 2, and 5, of the drawings is not necessary to be illustrated; it is employed to exhaust the hot air from the said compartment 1', or to force the cold air from the cold air generator 6, into the said storage compartment.

The fan 22, is driven by means of the belt 16, passing over the pulley 17, upon the shaft 15, the said belt being connected to the pulley on a motor shaft not required 85 to be shown. The said fan 22, is constructed to exhaust the impure, hot air from the compartment 1', of the car through the pipes 11, and 12, as hereinbefore described, and after this has been accomplished, to force or blow the cold air from the cold coil box or cold 90 air generator or conduit 6, into the opposite end of the car through the pipe 7, the said valves 20, and 21, being simultaneously opened by grasping the long lever 30, at 31, as hereinafter more fully described, which at the same time closes or shuts down the valve 23, in the 95 pipe 14. The said long lever 30, is fulcrumed upon the fork 32, of the standard or post 33, secured to the side of the cold coil box or cold air generator or conduit 6, as shown upon Fig. 6 of the drawings. The opposite end of said long lever 30, has secured thereto at 34, the 100 forked link 35, and to the lower end of said forked link 35, the swiveled link 36, is connected and the opposite end of said link 36, is swiveled to the valve 20. To the opposite end of the said long lever 30, near the point 31, thereon I swivel the long link 37, and to the lower end 105 of said long link 37, is swiveled at one end the short link

38, and the opposite end thereof is movably connected to the valve 23. The shorter lever 40 is fulcrumed to the fork 41 of the post 42, secured to the top of the cold coil box or cold air generator or conduit 6 near one end thereof, and the longer end 43 of the said lever 40 is swiveled to the lever-link 44 at one end and the opposite end of said lever-link is movably connected to the double-ended-forked-link 45 and to the said link is connected the valve 21 by means of the link 46. The shorter end 50 of the said shorter lever 40 is movably connected to the double-ended-forked-link 51 at one end, and the opposite end thereof is movably connected to the long lever 30, as shown in Fig. 6 of the drawings.

15 It will readily appear that when the operator grasps the long lever 30, at the point 31, as hereinabove stated, and elevates that end of said long lever 30, that the valve 23, will be opened, the valve 20, closed and the valve 21, will also be closed. All the impure air hereinbefore referred to, contained in the closed, loaded car, will by the suction and exhaust operation of the fan 22, be forced into the outer air through the pipe 14. The loaded car now being purified by removing the air accumulated therein while the fruits in the boxes were 20 being stored therein, the operator again grasping the long lever 30, at the point 31, thereon, reverses and depresses the said long lever 30, by placing the same in the position shown in full lines upon Fig. 6, closing the valve 23, within the pipe 14, opens the valves 20, and 21, and the blowing operation of the fan 22, forces the cold air which remained undisturbed in the cold coil box or cold air generator 6, while the car was being emptied of foul air contained therein, now blows the cold air from the said box or generator 6, through the 25 pipe 7, into the tanks or compartments 4, and 4', thence through the opening 8, 8', in the partition 8'', and into the storage compartment 1', of the car upon the boxes 2, therein, against the baffle plate 9, and downward around the boxes 2', the openings 10, and 10', in the 30 partition 10'', being closed by the pivoted covers 10''. This operation is continued until the thermometers 25, in the pipes 7, and 11, indicates that the temperature of the air in the car has been reduced to the desired point for preserving the perishable fruits or other articles contained in the boxes 2, and 2', of the compartment 1', of the car. The pipes 7 connecting the cold air generator with the tanks 4, 4', the central storage compartment 1', the two-end tanks 5, 5', the pipe 11, connecting one of the said tanks 5 with the fan 22, and

the pipe 13, leading from the fan to the cold air generator 6, form an endless chamber or conduit.

What I do claim as my invention and desire to secure by Letters Patent, is—

1. In a refrigerating apparatus, a chamber, a conduit connected therewith provided with an opening to the atmosphere, a blower and valve, said valve being between the blower and the chamber, and being adapted to control the passage through the conduit, a second valve adapted to control the opening to the atmosphere, and means connecting said valves whereby they may be intermittently and simultaneously operated, and a coil in the conduit.

2. An apparatus for cooling perishable fruits and like articles, comprising a central storage compartment, tanks or compartments at each end of the said storage compartment, a cold air generator connected with said central storage compartment and with the end compartments forming one continuous conduit, said conduit having an opening to the outer atmosphere, an apparatus comprising a blower and three valves, one of said valves controlling the opening to the outer atmosphere, the other valves cooperating with each other to inclose the cold air within the generator, and means for simultaneously operating the said three valves.

3. A refrigerating apparatus, comprising a central storage chamber, a cold air generator connected therewith forming one continuous chamber, said chamber having an opening to the outer atmosphere, a blower and three connected valves, the said valves being located between the said central storage chamber and the blower, two of said valves being adapted to control the passage of air through the generator and the other valve being adapted to control the opening from the continuous chamber to the outer atmosphere.

4. A refrigerating apparatus, formed of one continuous chamber, comprising a central storage compartment, a cold air generator provided with a coil therein, said generator having an opening to the outer air, and means for communication between the said central storage compartment and the cold air generator, an apparatus for exhausting the warm air from the central storage compartment, and an apparatus comprising three connected valves, one of said valves being adapted to control the opening from the cold air generator or conduit to the outer air, and the other two valves adapted to inclose the cold air within the cold air generator or conduit.

5. A refrigerating apparatus comprising a storage chamber, tanks at the ends of said storage chamber, a cold air generator having an opening to the outer atmosphere, and exhaust apparatus and three valves, one of said valves being adapted to control the opening between the cold air generator and the outer atmosphere, the other two valves inclosing the cold air within the generator, and means whereby said three valves may be simultaneously operated.

In testimony whereof, I have signed my name to this specification, in the presence of two subscribing witnesses.

CHARLES F. EDSON.
